UNITED STATES PATENT OFFICE

JOHN J. GREEBE, OF MIDLAND, MICHIGAN, ASSIGNOR TO THE DOW CHEMICAL COMPANY,
OF MIDLAND, MICHIGAN, A CORPORATION OF MICHIGAN

AUTOCLAVE

Application filed April 23, 1930. Serial No. 446,679.

The present invention relates to autoclaves adapted for conducting reactions in liquid media at high temperature and under high pressure when it is desired to include a metallic catalyst in the reaction mixture.

If it be attempted to conduct a reaction in a liquid medium which is an electrolyte, and two dissimilar metals are in contact therein, a galvanic couple is formed and electrochemical action proceeds with the solution of one of the metals and the deposition thereof upon the other metal. If, for instance, it be desired to conduct such a reaction in the presence of copper as catalyst at a temperature and pressure at which copper is not safe or economically useable as the wall of the pressure vessel, then it becomes necessary to use a stronger metal for the vessel and to adopt a construction in which no electrolytic action shall be set up which will either weaken the pressure vessel by corrosion thereof or injure the metallic catalyst by deposition of another metal thereon. Such autoclaves have been made of steel or other structural metal suited to the pressure and temperature, lined with the catalyst metal such as copper, such lining being extended through all openings, such as those for inlet and outlet of material, and into contact with ducts or piping of the same metal whereby it has been intended to prevent any of the liquid being reacted from contacting with two dissimilar metals.

The difficulty met with in such construction is to secure a perfect lining and perfect continuity of the lining with the ducts to and from the autoclave. Should the lining be perforated under pressure or suffer gradual deterioration or should leakage occur in any manner, as at openings closed by flanges or other means, or at welds or seams in the metal, the electrolyte would then get into the space between the lining and the pressure shell whereupon corrosion would occur followed by weakening of the pressure vessel and deterioration of the catalytic activity of the lining.

I have invented a method of introducing a catalytic metal into an autoclave or pressure vessel made of a dissimilar metal in which the defects of previous practice are

entirely overcome in a very simple, economical manner.

To the accomplishment of the foregoing and related ends, the invention, then, consists of the means hereinafter fully described and particularly pointed out in the claims, the annexed drawings and the following description setting forth in detail certain means for carrying out the invention, such disclosed means illustrating, however, some of the various ways in which the principle of the invention may be used.

I construct the autoclave or pressure vessel of a metal suited to contain the liquid to be reacted, which vessel may be of large or small diameter, preferably of tubular shape for high-pressure high temperature reactions whereby thickness and weight of the autoclave is kept at a minimum. I then place a body of the catalytic metal in the autoclave, insulate it therefrom to prevent its contact with the wall, using an insulating material substantially unreacted upon by the charge, but without attempting to prevent contact between the liquid reactants and the pressure vessel wall. A variety of constructions may be employed, preferred and alternative forms of which are illustrated in the drawings.

In said annexed drawings:

Fig. 1 represents in broken longitudinal cross-sectional view, a cylindrical autoclave of preferred type showing alternative arrangements of parts. Fig. 2 is a longitudinal cross-sectional view of a similar autoclave showing a still further alternative construction.

Referring further to Fig. 1 of the drawings, 1 is the pressure vessel, which will preferably be cylindrical and of any convenient length, the ends of which may be closed by removable covers as at 2, or may be sealed by welding as at 3. Inlet 4 for the liquid to be reacted and outlet 5 are provided, to which suitable ducts may be connected, as indicated in dotted lines. Within the pressure vessel is a tube of the catalyst metal, shown at 6 as a plain tube and at 6' as a corrugated tube. Such tube may be perforated if desired. The tube 6 or 6' is supported

out of contact with the pressure vessel by means of insulating plugs or disks 7 and 7', which disks fit loosely within the pressure vessel and are perforated to permit flow of 5 the reaction mixture into and out of the tube 6. A body of additional catalyst metal 8 may be filled into tube 6, completely or partly filling the same. Such metal may be in the form of sheet-clippings, rings, borings, 10 or the like, having an extended surface exposed to contact with the liquid contents of the vessel. Otherwise the simple, straight, corrugated, or otherwise fabricated tubular construction of the catalytic metal may be 15 more simply employed. It will be seen that the reaction mixture fills the entire pressure vessel 1 surrounding and filling the catalyst metal tube but that the insulating members, 7 and 7', prevent contact between the metal 20 wall 1 and catalyst metal 6 which are dissimilar and would, if contacted, set up electrolytic action.

In Fig. 2 another alternative form of construction is shown. Here the catalyst metal 25 in a form having an extended surface, represented at 8, is charged into the reaction vessel 1 provided with a lining of insulating material, here shown as in sectional form composed of rings 9 which are inserted into 30 the reaction vessel forming therein an inner chamber. The ends of this chamber are closed by the perforated plugs 10 and 10'. Here no tube or capsule of the catalyst metal is used as indicated in Fig. 1, but a body of 35 clippings, borings or the like of the catalyst metal is charged directly into the lined reactor. The character of insulation used will depend upon the nature of the reactants and the precise shape, form or manner of application thereof is immaterial. The sectional members 9 may be entire rings or may be 40 made up of segments as desired. I have found that marble, limestone, sintered magnesia, glass, stoneware, silica, or ceramic materials in general, may be used for insulating lining, the choice depending upon the 45 nature of the liquid reactant mixture. For an alkaline liquor a basic material such as marble or sintered magnesia may be selected, while for an acid liquor a material such as 50 glass or silica may be more suitable. For most purposes a steel reactor pressure vessel may be used, the catalyst metal being chosen as required for the process. In some 55 cases metals other than steel may be required for the pressure vessel, but its use will be in general preferable on account of low cost, strength, and workability.

To illustrate the advantages of my improved autoclave, its use in the production of a phenol by reaction between a halogenated aromatic hydrocarbon and aqueous alkali will be described. For instance, the reaction 60 between chlorobenzene and aqueous caustic soda may be carried out in the presence of

copper as catalyst within the temperature range between 300° and 350° C. in about the same length of time and with equally satisfactory results as in a temperature range between 350° and 400° C. without such catalyst. 70 The lower temperature range is manifestly advantageous because the pressure at the lower temperature is so much less than that at the higher temperature and for other obvious reasons. I may operate the autoclave 75 of the type herein described intermittently upon batches charged thereto, or in a continuous manner by flowing a stream of the mixture to be reacted through such autoclave or through an extended tubular system containing an insulated catalyst container disposed therein in like manner.

The reactor in this instance will preferably be of steel which is suitable for the temperature and pressure involved and upon which the reacting liquid is substantially non-reactive, and marble insulation may be used. Were, however, contact between the copper and the walls of the reactor permitted in the presence of the reactants, the steel pressure vessel would be attacked and corroded and iron would tend to be deposited on the copper, entailing a two-fold disadvantage, i. e. reduction in strength of the pressure vessel 90 and reduction of catalytic activity or eventually entire elimination of the catalytic action of the copper. Where, however, the catalyst is disposed as herein described, no such action can occur and repeated charges of material may be reacted and withdrawn, or a continuous reaction may be carried out over long periods of time, without attention to the catalyst or pressure vessel being required, due to changes therein incident to electrolytic action 95 between dissimilar metals.

Where a limited catalyst metal surface sufficient for the purpose is required, the catalyst may be provided simply in the form of a sheet or shell or tube as in Fig. 1. Where, however, an extended surface is advisable, such may be readily provided by insulating the inner wall of the pressure vessel and charging thereto copper clippings or scrap, as indicated in Fig. 2, or by placing such clippings or scrap in a copper capsule, tube, or casing, as indicated in alternatively in Fig. 1.

It will be seen that I avoid entirely, first, the difficulties of construction involved in lining a pressure vessel with a dissimilar metal, and, second, the making and unmaking of connections to such lined vessel while retaining continuity of lining to avoid introduction of the reacting liquid into the space between the lining and the walls of the pressure vessel. I further avoid placing the catalytic metal under stresses due to pressure for which purpose it is usually not well suited and I am able to employ steel, iron, or alloys thereof well suited to high temperature 120 125 130

and high pressure work in simple forms without accurate fitting of catalyst metal thereto. I have described particularly the reaction for the hydrolysis of halogenated aromatic hydrocarbons by means of aqueous alkalis for production of phenols in the presence of copper but it will be obvious to those versed in the art that other reactions may be carried out in like manner in the presence of other catalysts than copper as may be required for the specific problem in hand. For instance, in reactions involving hydrogenation under pressure, wherein nickel or other metallic catalyst is used, such catalyst may be provided advantageously in the manner herein described.

Other modes of applying the principle of my invention may be employed instead of those explained, change being made as regards the mechanism herein disclosed, provided the means stated by any of the following claims or the equivalent of such means be employed.

I therefore particularly point out and distinctly claim as my invention:—

1. In apparatus of the character described, the combination of a metal pressure vessel, a dissimilar catalyst-metal disposed therein, and electrically insulating means preventing contact between said catalyst-metal and said vessel.

2. In apparatus of the character described, the combination of a steel pressure vessel, a dissimilar catalyst-metal disposed therein, and electrically insulating means preventing contact between said catalyst-metal and said vessel.

3. In apparatus of the character described, the combination of a steel pressure vessel, copper catalyst-metal disposed therein, and electrically insulating means preventing contact between said catalyst-metal and said vessel.

4. In apparatus of the character described, the combination of a tubular metal pressure vessel, a dissimilar catalyst-metal tubular member therein, and electrically insulating means preventing contact between said catalyst-metal and said vessel.

5. In apparatus of the character described, the combination of a metal pressure vessel, a dissimilar catalyst-metal having an extended surface disposed therein, and electrically insulating means preventing contact between said catalyst-metal and said vessel.

6. In apparatus of the character described, the combination of a tubular metal pressure vessel, a dissimilar catalyst-metal tubular member therein, a body of catalyst-metal having an extended surface within said member, and electrically insulating means preventing contact between said catalyst-metal and said vessel.

7. In apparatus of the character described, the combination of a steel pressure vessel,

copper catalyst-metal disposed therein, and electrically insulating means of a basic nature preventing contact between said catalyst-metal and said vessel.

8. In apparatus of the character described, the combination of a steel pressure vessel, copper catalyst-metal disposed therein, and electrically insulating means of marble preventing contact between said catalyst-metal and said vessel.

Signed by me this 19th day of April, 1930.

JOHN J. GREBE.
